TOOL FOR SPLICING CABLES

Isidore Jacoel, Buffalo, N. Y.

Application December 12, 1942, Serial No. 468,796

6 Claims. (Cl. 57—23)

This invention relates to a tool for tightening or handling the strands of wire cables for splicing one cable part with another cable part and also the method of using this tool.

It is the object of this invention to provide an improved tool and method of splicing cables whereby this work can be effected more easily, rapidly and efficiently than has been possible heretofore and thereby expedite the output and reduce the cost of work of this character.

In the accompanying drawings:

Fig. 1 is a perspective view of a cable which is provided with a loop containing a thimble and of which the strands of the body and loose end on opposite sides of the loop are adapted to be spliced by the use of this improved tool and method of operation.

Fig. 2 is a similar view of the cable showing the preliminary untwisting of part of the cable body preparatory to splicing the same with the loose end of the loop.

Fig. 3 is a perspective view of the preferred form of the tool embodying this invention.

Fig. 4 is a fragmentary plan view, on an enlarged scale, of the front end of this tool.

Fig. 5 is a perspective view showing the tool applied to a strand of the loose end which has been interwoven with strands of the cable body preparatory to tightening the respective loose end strand on the body strands.

Fig. 6 is a diagrammatic cross section, on an exaggerated scale, showing the relative position of the body strands, the loose end strand and the tool corresponding to Fig. 5.

Fig. 7 is a view similar to Fig. 5, but showing the tool turned and the loose end strand wound thereon for tightening the same in the body strands.

Fig. 8 is a cross section similar to Fig. 6 but showing the relative position of the tool and the form of the loose end strand corresponding to Fig. 7.

Fig. 9 is a view similar to Figs. 5 and 7, but showing the tool tilted laterally relative to the cable for producing a comparatively abrupt or sharp bend in the same around a body strand in order to interlock the respective strands.

Fig. 10 is a cross section similar to Figs. 6 and 8 showing the parts in a position corresponding to Fig. 9.

Fig. 11 is a plan view showing a completed splice between the strands of the cable body and loose end and securing the thimble within the loop of the cable.

In the following description similar reference

characters indicate like parts in the several figures of the drawings.

In the drawings, the numeral 20 represents the body of a wire cable provided with a loop 21 which encloses a thimble 22 and one side 23 of which forms a continuation of the cable body while the opposite side 24 thereof terminates in the loose end 25 of the cable.

Fig. 1 represents the thimble arranged within the loop of the cable while the latter is still open or unspliced and held by a clamping device 26 which is adapted to be rotated and which may be of any suitable construction, but preferably of the general character shown in Letters Patent of the United States, No. 2,028,610, dated January 21, 1936.

While the loop of the cable and the thimble therein are held by the clamping device the body of the cable is secured to and held against turning by a stationary gripping or holding device 27 consisting preferably of a vise of any usual or well known construction. The loop and thimble holding device is provided with a braking or retaining means 28 whereby the loop and thimble holding device may either be held against turning or permitted to turn at intervals as the splicing of the cable proceeds in the manner set forth in said patent.

The loop and thimble holding device and the cable holding or gripping device may be mounted on any suitable stationary support, such for example as an ordinary work bench.

After the loop and thimble have been secured to the clamping device 26, as shown in Fig. 1, this clamping device is turned backwardly a sufficient extent to untwist, separate or loosen the strands of the cable adjacent to the inner end of the thimble, the strands 29 of the cable thus untwisted being shown separated to an exaggerated extent in Fig. 2 for the purpose of more clearly illustrating the method of operation of this invention.

The turning backward of the loop and thimble for untwisting the cable is effected by a manually operated turning rod 30 which is passed through the thimble and loop of the cable and the adjacent part of the clamping device, as shown in Fig. 2, and then turning backwardly or in a direction which will cause the strands 29 of the cable body adjacent to the thimble and loop to untwist.

Preparatory to splicing the cable the ends of the strands of the loose end of the cable are separated, unraveled or frayed, as shown at 31 in Fig. 2.

The several strands of the unraveled loose end

are now individually interwoven or interlaced successively with different strands 29 of the untwisted part of the cable and interlocked therewith in accordance with this invention as follows:

One of the loose end strands 31 is passed or threaded underneath a separated body strand 29 on one part of the periphery of the cable, then tightened and interlocked therewith and in like manner each of the remaining strands are likewise threaded, tightened and interlocked successively with different body strands around the periphery of the cable, this operation being repeated continuously until the determined number of tucks is completed. During the interweaving operation of the cable body and loose end, the splice is subjected to a hammering operation, as required, to produce a smooth and finished splice. This tightening of the loose end strands and interlocking of the same with the body strands is easily, conveniently and expeditiously effected by the splicing tool which forms part of this invention and which is constructed as follows:

The numeral 32 represents the body or shank of the tool which preferably has the form of a cylindrical rod. At its front end this body rod is provided with a coupling or receiving slot 33 which extends longitudinally rearward from the front end of the tool body and diametrically from one side of its periphery to the other. On its periphery the tool body is provided with a circumferential winding groove 34 which intersects the longitudinal receiving slot 33 slightly in front of the inner end 35 of this slot, as best shown in Fig. 4. At its rear end the shank of the tool is provided with a handle 36 which preferably has the form of a rod extending transversely through the shank and whereby the tool is turned by the hands of the operator. When using this tool its front part is attached to one of the loose end strands 31 which has been interwoven with one of the cable strands on the upper side of the cable and is projecting laterally therefrom, which attachment is effected by placing the slot 33 of the tool on the respective loose end strand 31 close to the cable until this strand engages with the inner end 35 of this slot, as shown in Figs. 5 and 6, whereby the front end of the shank straddles this strand in the manner of a fork and causes the same to be coupled and compelled to turn together upon rotating the shank about its longitudinal axis.

After the shank or body of the tool has been coupled with the respective loose end strand the shank is turned about its axis in a direction in which it rolls on the cable body toward the root or base of the respective loose end strand, thereby tightening the loose end strand by winding the slack in the latter between the shank and the last body strand 29 with which this loose end strand is interwoven around the periphery of the shank, as shown in Figs. 7 and 8. This wound up portion 37 of the loose end strand enters the circumferential groove 34 of the shank and engages the bottom thereof which latter acts as a drum around which the loose end strand is wound. The extent of this turning movement of the shank for winding the loose end strand thereon depends on the amount of slack in the respective strand but in the drawings this turning movement is represented as three-fourths of a rotation from the place where the loose end strand is placed in the slot 33 of the tool shank, as shown in Fig. 6, to the place where the loose end strand is wound sufficiently on the tool shank to take up the slack therein and tighten the same

relative to the body strands 29 with which it is interwoven.

By employing a circumferential groove on the tool shank for the reception of the loose end strand the latter is prevented from moving lengthwise on the shank during the winding and tightening operation and instead is compelled to wind circumferentially around the shank and thus pull most effectively on the loose end strand which is being tightened. By extending the coupling slot 33 rearwardly so that its inner end 35 terminates a short distance rearwardly of the rear side or wall of the groove 34 that part of the loose end strand which is arranged within the coupling slot 33 together with its free tail end are held mainly on one side of the path of that part of this strand which is to be wound around the bottom of the groove 34 thereby enabling this last mentioned part of this strand to enter this groove without liability of any of its parts catching on the corners between the coupling slot 33 and the winding groove 34 where this strand bends from this slot into said groove.

After the loose end strand has been wound on the shank of the tool for tightening the strand in the cable body strands the tool is rocked or tilted in a plane crosswise of the axis of the cable body, as shown in Fig. 9, so that the front end of the shank which is attached to the respective loose end strand will be lifted or moved laterally relative to the cable body, thereby causing that part of the loose end strand which passes forwardly and upwardly around the last interwoven body strand 29 to be bent sharper and more abruptly, as best shown at 38 in Fig. 10, and thus firmly interlock the parts of the respective body strand and loose end strand and hold the same tightly in place until it is ready for the next interweaving or splicing operation. After this loose end strand has been thus tightened and interlocked with the respective body strand the tool is removed therefrom and utilized in the same manner for tightening and locking the next following loose end strand which has been interwoven with the body strands. This operation is repeated step by step on each loose end strand and successively on the several strands until all of the loose end strands have been interwoven a determined number of tucks to the body strands.

From time to time the interwoven strands of the body and loose end of the wire cable are hammered so as to form a smooth and finished splice, as shown in Fig. 11.

In the preferred construction the handle of the tool is arranged on the shank at an angle of about 45 degrees relative to the coupling slot 33 of the shank, so that the handle will be more nearly in a horizontal position when applying the slot 33 vertically to a loose end strand, as shown in Fig. 5, and also when tilting the shank with the slot 33 in about a horizontal position, as shown in Fig. 9, thereby enabling the operator to manipulate this tool most conveniently during the most important stages of the splicing operation.

I claim as my invention:

1. A tool for tightening the strands of a cable for splicing the same, comprising a rod provided in its front part with a longitudinal slot opening at the front end of the rod and adapted to receive a strand of the cable which is to be tightened.
2. A tool for tightening the strands of a cable for splicing the same, comprising a rod provided in its front part with a longitudinal slot opening at the front end of the rod and adapted to receive
